UNITED STATES PATENT OFFICE.

LUIGI PAVIA, OF ALLENTOWN, PENNSYLVANIA.

SHUTTLE.

Application filed February 8, 1928. Serial No. 252,865.

There is a type of shuttle tension devices in which coacting means, one of which is normally urged crosswise of the thread, maintain a bend or bends in the thread to tension it, usually in a zig-zag form. It has been proposed to adapt such coacting means to operatively receive the thread in the automatic replenishing of the supply of the thread or filling of the shuttle by constructing the stated one thereof so that when the shuttle, having received the fresh filling package, moves across the loom said means will be drawn back by the lateral pressure thereon of the filling as the latter tautens: for example, see my application, Serial No. 166,298. I have found, however, that the tension device sometimes fails to become threaded in this manner, but that if the said normally urged one of the two coacting means forming such device be repressed by means independent of the filling the threading of said device will infallibly occur as intended. To this end I provide in the shuttle a represser for the normally urged means, and this represser is actuated by some agency passed by the shuttle in its flight. Such agency may be, for example, the top of the warp shed, and while of course this will act on the represser on every flight of the shuttle and so on every flight cause the tension device for a period during such flight to be inactive to exert tension, near the end of the flight, or just before the shuttle enters the box being then approached, it will release the represser and permit the tension device to establish the tension in the final part of such flight.

I further provide means for preventing the twirling of the thread or filling around the package when being drawn therefrom from possibly causing failure of the thread to be caught fully in the tension device.

I have shown my invention applied to a shuttle such as is shown in my mentioned pending application, but only by way of example,

Fig. 1 being a plan of a shuttle embodying the invention;

Fig. 2 is a side elevation, partly broken away; and

Figs. 3 and 4, sections on lines 3—3 and 4—4, respectively, of Fig. 2.

The shuttle body 1; cavity 2 for filling package 3; filling channel 4 and groove 5 on the top near the forward end of the body 1; lateral notch 6 forming the filling outlet in the front side of the shuttle; casing 7 of the

tension device fitted in said body; the means of said device coacting to maintain bends in and thereby tension the filling, one comprising arbor 10 suitably journaled at its ends in the casing, a laterally extending arm 10^a and other (thread-guiding) upwardly extending hook-shaped arms 10^b formed with arched tails 10^c having cam-surfaces 10^d, and the other comprising a series of individually movable thread-guides 14 fulcrumed on a pin 13 and extending laterally across arms 10^b and in alternation therewith and having beaks 14^b inclined upwardly and toward the front of the shuttle; elastic means, as a rubber band 11, normally urging the first of said coacting means to the position shown in Fig. 3—i. e., bearing against the upper end of the slot 7^a in which plays the arms 10^a against which such band 11 bears; elastic means, as springs 15, normally holding the thread-guides 14, forming the other of said coacting means, against the upper ends of other slots 7^c, are or may be all the same as in my said application, to the end that if the thread or filling A is held taut and caused to bear down on cam-surfaces 10^d and then, after passing the hooks at 10^c, it is shifted toward the front of the shuttle past the beaks 14^b, it will come into the tensioning control of said coacting means. The casing end walls usually will be recessed at 18 to receive the thread, and the casing has a wall 19 forming with surfaces 10^e of the means 10 a V-shaped thread entrance, and there will also usually be a plate 20 or equivalent to form a sharpened nose 20^a overhanging channel 4 and notch 6, so that as the shuttle moves to the left in Figs. 1 or 2 after receiving a fresh filling package 3 the thread (attached to some part of the loom) will come into the tensioning control of said coacting means, as stated, and also in groove 5 and, on the return stroke, form in a bight and extend from the filling outlet 6, caught under nose 20^a and come fully into the control of the tension device.

For maintaining the proper tension, which according to the goods to be woven is moreover not always in practice the same, the said normally urged one of the two coacting tensioning means should oppose a certain degree of resistance to the filling. Such resistance may on occasion be greater than the filling can overcome when the automatic threading is to occur, so that the filling may fail to pass the beaks 14^b, or some of them. Hence I provide the represser, as follows:

Said represser is a blade 21 fulcrumed on a pin 22 in a slot 23 in one side of the shuttle body, being movable in a vertical plane to limits afforded by a slot 21^a therein receiving a pin 24. At its upward limit it protrudes, its protruding portion being rounded or forming a cam surface; it is normally held at its upward limit by a spring device 25. Its free end depends and is notched, as at 10 21^b, to straddle the arm 10^a of said normally urged one of the coacting tensioning means.

When the shuttle moves to the left after receiving (from the shuttle box—not shown—at the right) a fresh filling package and enters 15 the shed B of warp, with the thread trailing it, represser 21 is depressed by the top of the shed and so represses the normally urged one of the two coacting means, thus relieving the thread of that function and leaving it, tautened, only to slip over the beaks 14^b. The represser remains depressed until the shed (or it may be some other obstruction provided on the loom) is passed, whereupon, before the shuttle enters the other box, it rises, releasing 25 said means so that the tension is exerted on the thread at the end of the shuttle's flight. If for any reason the thread should not of itself slip over the beaks the hooks 10^c will positively cause it to do so on the return flight of the 30 shuttle: and in this aspect of my invention it is broadly new to provide, with thread guiding means, (such as the beaked elements 14), movable means (such as 21 and lever 10—10^a—10^b afford), having a part (as 21) 35 thereof exterior of the shuttle and to be engaged by an actuating instrumentality extraneous of the shuttle, for moving the thread past the first means.

It has been found that the twirling of the 40 thread around the package 3 as it is paid off therefrom sometimes causes a failure thereof to come into full engagement with the tension device. Wherefore, I provide further a thread or filling trap here consisting of an 45 upstanding plate 26 arranged in cavity 2 and having a horizontally elongated opening 26^a provided with a downward V-shaped thread

entrance 26^b thereto. The taut thread on the initial twist will enter opening 26^a and thereby become trapped or held in a position so 50 depressed that it cannot fail to be fully engaged in the tension device.

Having thus fully described my invention, what I claim is:

1. In combination, a shuttle body, a thread-guiding means normally urged in one direction and yieldable in the opposite direction, the thread being adapted to bear against the side of said means facing the first direction and move it in the second direction, thread-guiding means arranged to be passed by the thread on its moving the first means in the second direction and thereby adapted to coact with the latter to maintain a bend in the thread, and movable means in the shuttle, 60 actuatable at a point extraneous thereof, for moving said first means in the second direction.

2. In combination, a shuttle body, a thread-guiding means normally urged in one direction and yieldable in the opposite direction, the thread being adapted to bear against the side of said means facing the first direction and move it in the second direction, thread-guiding means arranged to be passed by the 70 thread on its moving the first means in the second direction and thereby adapted to coact with the latter to maintain a bend in the thread, and movable means in the shuttle, having a part thereof exterior of the shuttle 75 and to be engaged by an actuating instrumentality extraneous of the shuttle, for moving said first means in the second direction.

3. In combination, a shuttle body, a thread guiding means arranged to be passed by the 85 thread and with which the thread is thereupon adapted to be held in guided engagement therewith, and movable means in the shuttle, having a part thereof exterior of the 90 shuttle and to be engaged by an actuating instrumentality extraneous of the shuttle, for moving the thread past the first means.

In testimony whereof I affix my signature.
LUIGI PAVIA.
